INVENTOR.

JENNIE S. MOSELER
BY *A. B. Bourneau*
ATTORNEY.

UNITED STATES PATENT OFFICE.

JENNIE S. MOSELER, OF CHICAGO, ILLINOIS, ASSIGNOR TO C. M. CARR DENTAL MANUFACTURING COMPANY, OF DENVER, COLORADO, A CORPORATION OF COLORADO.

DENTAL INSTRUMENT.

1,402,525.

Specification of Letters Patent.

Patented Jan. 3, 1922.

Application filed March 17, 1921. Serial No. 452,965.

To all whom it may concern:

Be it known that I, JENNIE S. MOSELER, a citizen of the United States, residing at Chicago, in the county of Cook and State of Illinois, have invented certain new and useful Improvements in Dental Instruments, of which the following is a specification.

My invention relates to dental instruments, more particularly adapted for use for removing calcareous deposits or scale from natural teeth and affecting the displacement of the calculia from any straight, curved or irregular surface in the direct line of force applied in the drawing of the tool and for planing the surfaces of the teeth, all of which results in the elimination of scale and resultant inflammatory conditions of the gum and pus formations and consequent loosening of the teeth which is known as pyrrhoea.

The object of my invention is primarily improvements over the dental tool covered by Letters Patent to Cassius M. Carr, Patent No. 1,138,355, issued May 4, 1915, and my application for Letters Patent filed May 3, 1920, Serial No. 378,473 and the objects of these improvements are: First, to provide an instrument of this class with a shorter and differently shaped shank while maintaining the same length operating and cutting edge supporting portion thus bringing the working portion closer to the handle of the instrument so that said working portion is more definitely under the control of the operator providing an instrument more easily controlled in operation; second, to provide a dental instrument with a short shank of this class in which the axial line of the handle passes intermediate the cutting edge and the guiding or supporting portion of the

shank or approximately in the middle of the concave, convex or straight cutter supporting portion of the shank instead of passing at the cutting edge, so that the central handle alignment is between the supporting portion and the cutting edge of the instrument, thus providing a maximum control of the cutting edge of the instrument; third, to provide an instrument with a shank of this class with a differently shaped cutting or planing portion than known before my application Serial No. 378,473, so that it is efficient and not liable to injure the gum contiguous to the tooth when operating the instrument; fourth, to provide an instrument of this class which

is very easy to manufacture and is durable and efficient.

With these and other objects in view as will appear hereinafter my invention consists of certain novel features of construction, combination and arrangement of portions as will be hereinafter described in detail and particularly set forth in the appended claims reference being had to the accompanying drawings and to the characters of reference thereon which form a part of this application.

In carrying out my invention I provide a series of tools each adapted for use upon a pre-determined shaped portion of a tooth and each has a cutting edge and a guiding portion. The guiding portion serves to engage with the tooth in advance of the cutting edge to steady the same while the cutting edge is back of the line of the axis of the handle approximately an equal distance from alignment with the axis of the handle so that the axis of the handle is intermediate the cutting portion and the guiding or supporting portion, so that the instrument is more easily controlled and not so liable to turn or slip when in use.

In the drawings Figure 1 is an enlarged side elevational view of one of my instruments showing the handle fragmentarily and showing the shape of the shank and position of the cutting edge and guiding portion relatively to the handle axis; Fig. 2 is an end view thereof and showing, by dotted lines, varying positions of the eight different cutting edges relatively to the octagonal sides of the handle thus showing the angularity of the cutting edge to the sides of the handle of the different tools in each series; Fig. 3 is a side elevational view of one of the instruments with a straight shank adjacent to the cutting edge as distinguished from that of Fig. 1 with a concave shank adjacent to the cutting edge; Fig. 4 is an end view thereof; Fig. 5 is a similar view to that of Fig. 3 showing the shank in convex form adjacent to the cutting edge; Figs. 6, 7 and 8 are similar views showing the tools in modified form with lesser offset shank portions throughout; Fig. 9 is an enlarged view looking toward the cutting edge of the instrument; Fig. 10 an edge view thereof; Fig. 11 an end view thereof; Fig. 12 is an enlarged edge view of a concave adjacent to the cut-

ting edge form of shank showing the cutting or planing portion and Fig 13 is a similar view of the convex adjacent to the cutting edge form of shank.

5 Similar characters of reference refer to corresponding portions throughout the several views of the drawings.

The handle 1, right angle shank portion 2, curved shank portion 3, angular portion 4, 10 cutter supporting portion 5 and cutter portion 6 constitute the principal portions of my dental instrument.

For the sake of illustration I have shown the handle portion 1 octagonal and extending laterally there from by means of a curve 2^a at right angles is the right angled shank portion 2 which extends a short distance and gradually tapering, then provided with a curved shank portion 3, then extending 20 backwardly in angular form, is the portion 4, which is provided on its extended end with the cutter supporting portion 5 which extends approximately one half the distance from the cutter to the intersection 25 of the curve 3 and it is shaped differently with the different instruments dependent on the particular shape of the place desired to use any instrument of the particular series upon. These portions 5 are formed into 30 three definite series consisting of a concave form on the side from which the cutter projects, shown best in Figs. 1, 6 and 12 of the drawings, another straight, shown best in Figs. 3, 7 and 10 of the drawings, the other 35 convex on the side from which the cutting edge projects shown best in Figs. 5, 8 and 13 of the drawing. The cutting portion 6 it 40 will be noted leaves the shank at an obtuse angle 6^a which angle is taken from the portion of the shank where the blade attaches and the lower edge is provided with a side 6^b at a slightly acute angle with 6^a and the end portion 6^c rounded, so the instrument 45 serves as a probe to press the tissues back without wounding them while the instrument is in use.

It will also be noted that these sides are rounded at the sides 6^d shown best in Figs. 9, 10 and 11 so that they do not injure the

gums at the side edges of the cutting portion 50 of the instrument.

The cutting edges of the instruments it will be noted are positioned in conformity with octagonal sides of the handle so that with an instrument with eight sides there are 55 eight differently positioned cutting edges in the series conforming in position with the eight sides of the handle 1 as disclosed best in Fig. 2 of the drawings by dotted lines showing the varying positions of the cutting 60 edge and engaging end of the instrument.

It will be also noted that the axial line of the handle passes through the shank portion 5 between the cutting edge 6 and the other point of contact at a point approximately 65 midway between the two points of contact as shown in the drawings.

It is obvious that with the construction in the various forms that the operator is enabled to reach the surfaces of all the roots of 70 the teeth and remove all foreign substances between the teeth and the gum or tissue surrounding the teeth and leave the tooth with a smooth polished surface without grooves; that the shank of the instrument is so shaped 75 and arranged and the position of the cutter relative to the handle is so arranged that the operator can always hold the instrument in position depending upon the instrument used in the series for producing the proper re- 80 sults without causing grooves.

Having thus described my invention what I claim as new and desire to secure by Letters Patent is:

A dental instrument including, a handle 85 portion, a shank portion offset at a right angle therefrom then curved, then extending backwardly in a straight line on an angle to said handle portion, and a cutting edge positioned on the opposite side of the axial line 90 of said handle from the offset portion of the shank whereby the instrument is easily held in balance and therefore easily controlled while in use.

In testimony whereof, I have hereunto set 95 my hand at Chicago, Illinois, this 14th day of February, 1921.

JENNIE S. MOSELER.
